(57) **CLAIM**

The ornamental design for a portable skate/boot/glove dryer, as shown and described.

DESCRIPTION

FIG. 1 is a perspective view of the portable skate/boot/glove dryer in its environment showing my new design;

FIG. 2 is a front elevation view of the dryer of FIG. 1;

FIG. 3 is a top view of the dryer of FIG. 1;

FIG. 4 is a bottom view of the dryer of FIG. 1;

FIG. 5 is a left side elevation view of the dryer of FIG. 1;

FIG. 6 is a right side elevation view of the dryer of FIG. 1; and, FIG. 7 is a rear elevation view of the dryer of FIG. 1.

The broken lines shown in the drawings represent portions of the portable skate/boot/glove dryer that form no part of the claimed design.
